UNITED STATES PATENT OFFICE.

GEORGE E. SHOREY, OF FAIRFIELD, MAINE.

FOLDING TABLE.

SPECIFICATION forming part of Letters Patent No. 707,171, dated August 19, 1902.

Application filed January 20, 1902. Serial No. 90,513. (No model.)

To all whom it may concern:

Be it known that I, GEORGE E. SHOREY, a citizen of the United States of America, and a resident of Fairfield, Somerset county, State of Maine, have invented certain new and useful Improvements in Folding Tables, of which the following is a specification.

My invention relates to a folding table; but it may be applied to other articles which have folding legs or folding parts which it is desired to lock firmly in their extended position.

The folding tables now in common use are provided with braces for holding the legs in their extended position which lock automatically when the legs are opened out; but when the table is to be folded up it is necessary to release the lock or catch by hand, an operation which often requires considerable strength and is difficult for ladies and children.

The object of the present invention is to provide a folding table in which the legs may be locked and unlocked without any manipulation of the parts. I accomplish this object by providing a dog or lock for locking and releasing the brace which holds the legs and so pivoting this dog that it may be thrown in or out of its locking position by gravity or by a slight motion of the table. When the table is standing in its normal position or when the under side of the table is less than ninety degrees from a horizontal position, then the dog will drop down and lock the brace; but when the table is turned over on its top then the dog will drop back and release the brace. Thus after the legs are folded out the act of setting the table on its feet will automatically act to lock it, and when it is turned over partially on its back for folding the legs down against the table the dog will automatically drop back and release the brace.

I illustrate my invention by means of the accompanying drawings, in which—

Figure 1 is a part side view and part central section with the legs extended. Fig. 2 is the same with legs folded, and Fig. 3 is a cross-section on the line xx of Fig. 1.

A represents the table-top, and BB are the legs, which are hinged to the cross-piece a by pins b'. To the cross-bar b, which connects the two legs, is pivoted the brace c, the free end of the brace lying and sliding in the

groove of the channel-piece d, which is secured to the under side of the table. This channel-piece is made long enough so that each of the braces lies in it at full length when the legs are folded in. The legs are held from extending beyond the desired point by the pin c², which engages the hook c', formed on the end of the brace. A spring f is provided for pressing the brace normally down into the groove of the channel-piece and for the further purpose of holding the legs against the under side of the table when they are folded. As here shown, I use a spring made of bent wire, the ends being coiled about the pin h, which extends through the channel-piece, with the extreme end resting against the table, the center of the spring forming a loop which saddles the edge of the brace and presses it at all times into the groove. The brace is locked in its extended position by means of a dog, which is thrown into and out of position by gravity.

The dog g is here shown as a straight piece of steel pivoted in the groove beyond the end of the brace when the latter is in its extended position and of such length that its end will just rest on the point or projection c², formed on the end of the brace, when the dog is in its down or locking position. When the dog is in its upper or unlocked position, the end of the brace will slide back over it, the end being tapered off for this purpose. When the table stands in its upright position, the dog will drop down and lock the brace, and when it is turned over on its back the dog will drop back into the position shown in Fig. 2, so as to allow the brace to slide back over it. A slot g' is cut in the dog to allow it to clear the pin h. It is evident that this device may be used on other articles besides tables—such as chairs, settees, step-ladders, &c.—where folding legs are used. As already stated, the table may be locked and unlocked by canting it slightly one way or the other from the vertical, and the handling of the locking mechanism is entirely avoided.

I do not wish to limit myself to the exact forms of parts herein shown by way of illustration, as, for instance, other forms of springs and other forms of dogs may be used.

I claim—

A folding table, comprising a top, a chan-

nel-piece secured longitudinally in the center of the under side thereof, a pair of dogs extending in opposite directions pivotally mounted in said channel-piece, a stop-pin adjacent to the end of each dog in the channel-piece, legs arranged in pairs pivotally secured to the top and adapted to swing inward, a brace-rod carried by each pair of legs having its free end slidably mounted in the channel-piece, and a spring to hold each brace in the channel-piece at all times, to hold the

braces in contact with the stop-pins while the dogs fall by gravity to engage the extreme ends of the braces when the legs are opened, and to hold the braces flat upon the dogs 15 when the legs are closed.

Signed at Brunswick, Maine, this 14th day of January, 1902.

GEORGE E. SHOREY.
